TRAINING-TYPE ROLLER SKATE

Samuel S. Day, New Haven, Conn.

Application January 29, 1952, Serial No. 263,790

4 Claims. (Cl. 280—11.2)

This invention relates to roller skates in general, and to safety-type roller skates in particular.

It is an object of the present invention to permit youngsters heretofore considered too young for the hazardous pastime of roller skating to indulge in this fascinating pastime with the full consent of their elders, by providing safety-type roller skates on which these youngsters may realistically imitate experienced older youngsters performing on normal free-wheeling roller skates, without being exposed to the well-known hazards involved in riding the latter.

It is another object of the present invention to provide safety-type roller skates on which youngsters of all ages with little or no experience on normal roller skates may learn to skate naturally, while being gradually exposed to the hazards from free-wheeling rollers as they gain more and more experience in and control over riding roller skates.

A further object of the present invention is to have provisions on roller skates for braking the front wheels or the back wheels, or both, at all times and especially when the skates are ridden in the customary manner, thereby to protect the rider, either fully or at least in part, from the hazards involved in riding free-wheeling roller skates.

Another object of the present invention is to provide on roller skates either for the front wheels or the back wheels, or both, a brake which is adjustable for the application of a variable braking force to these wheels, thereby to adapt the instant roller skates for training youngsters safely through progressive stages in the correct use of conventional roller skates.

It is a further object of the present invention to have the aforementioned brake provisions in the form of removable accessories for conventional roller skates, thereby permitting not only their separate purchase and ready application to conventional roller skates of all makes, but also their removal from the skates for the conventional use of the latter by youngsters who have the confidence and experience to ride them.

It is also among the objects of the present invention to have the aforementioned brake provisions of exceedingly simple structure so that they readily lend themselves to efficient and inexpensive mass production, and to devise these brake provisions so that they lend themselves to facile installation on and removal from conventional roller skates of all makes and sizes, as well as to facile adjustment for varying their braking force on the wheels of roller skates on which they are installed.

Other objects and advantages will appear to those skilled in the art from the following, considered in conjunction with the accompanying drawings.

In the accompanying drawings, in which certain modes of carrying out the present invention are shown for illustrative purposes:

Fig. 1 is a side elevation of a roller skate embodying the present invention;

Fig. 2 is a section taken substantially on the line 2—2

2

of Fig. 1, the dot-and-dash lines outlining the parts of the roller skate above the section line in Fig. 1;

Fig. 3 is a section taken on the line 3—3 of Fig. 1;

Fig. 4 is a fragmentary side elevation of a roller skate embodying the present invention in a modified manner;

Fig. 5 is a view similar to Fig. 4, but showing certain parts of the roller skate in section;

Fig. 6 is a perspective view of certain brake provisions shown on the roller skate of Figs. 4 and 5;

Fig. 7 is a fragmentary side elevation of a roller skate embodying the present invention in a further modified manner; and

Fig. 8 is a section taken substantially on the line 8—8 of Fig. 7.

Referring to the drawings, and more particularly to Figs. 1 to 3 thereof, the reference numeral 10 designates a roller skate having the customary foot rest 12 and front and rear wheels or rollers 14 and 16, respectively. The foot rest 12 consists of the usual telescoping toe and heel plates 18 and 20, respectively, which may be locked in longitudinally adjusted positions by bolts 22.

The front and rear wheels 14 and 16 are rotatably mounted, usually through intermediation of ballbearings, on fixed axles 24 in conventional front and rear mounts

26 and 28, respectively, which are identical in construction, though oppositely inclined to the foot rest 12 (Fig. 1). The conventional construction of a rear mount for the rear wheels is shown in Fig. 2, as well as on the skate in Fig. 5 in which the invention is embodied in a modified manner described hereinafter. This rear mount 28 comprises a generally U-shaped bracket 30 depending with its opposite legs 32 from the heel plate 20, and having on the opposite sides of its connecting yoke or base portion 34 depending flanges 36 and 38 which straddle the opposite legs 40 and 42, respectively, of another

U-shaped bracket 44. The bracket 44 has a portion of its connecting yoke or base 46 formed to provide a socket 48 for the press-fitted reception of the rear axle 24 on which the rear wheels 16 are rotatably mounted. Received in the bracket 44, and interposed between the base 46 of the latter and the base 34 of the bracket 30, is a rubber pad 50 which lends to the wheel mount shock-absorbing qualities. The several parts 30, 44 and 50 of the wheel mount 28 are held in their assembled relation

45 by a lock pin 52.

The roller skate described so far may be conventional in every respect, and forms no part of the present invention. In accordance with the present invention, there is provided on the roller skate a brake device 54 which, in the present instance, comprises a brake member 56 and a brake applicator 58. The member 56 may be a plate of any suitable brake material, in this instance wood, which is notched at both ends, as at 60 and 62, to provide front and rear prongs 64 and 66 which bear against the tops of the front and rear wheels 14 and 16, respectively, while clearing the respective wheel mounts 26 and 28 (Fig. 2). The rear notch 62 in the brake member 56 is of sufficient depth to clear the bolts 22 so as to permit ready extension or contraction of the foot rest 12 of the roller skate without obstruction from the brake member.

The brake applicator 58 is a screw which may be manipulated to force the prongs of the brake member 56 into braking engagement with the front and rear wheels 14 and 16. In the present instance, the brake member

56 and applicator screw 58 form a separate unit which may be installed on and removed from a conventional roller skate. To this end, the brake member 56 may be slid between the wheel mounts 26 and 28, and the applicator screw 58, which in this instance extends through

65 the wooden brake member 56 without being in threaded engagement therewith, receives a nut 70 of a conventional

70 engagement therewith, receives a nut 70 of a conventional

self-locking type (Figs. 2 and 3). If the brake member 56 were made of metal, the applicator screw 58 could be threaded directly into the brake member and the nut 70 could be dispensed with. In applying the brake device 54 after its installation on the skate, the applicator screw 58 is turned at its wing end 72 until the end of the screw bears against the foot rest 12. On continued turning of the applicator screw 58, the nut 70 will be backed against the brake member 56, thereby forcing the prongs 64 and 66 of the latter into braking engagement with the front and rear wheels 14 and 16, respectively, of the skate. The end of the applicator screw 58 bears in this instance against the toe plate 18 of the foot rest 12 (Fig. 3), and extends through the elongated slot 74 which is provided in the heel plate 20 for cooperation with the bolts 22 in the toe plate 18 to permit longitudinal extension or contraction of the skate.

The applicator screw 58 may be tightened to such an extent that the brake member 56 is considerably bent against the front and rear wheels 14 and 16 and substantially locks the same against free-wheeling even if a youngster on the skate should push the latter forward on the ground. In this respect, skates with the instant brake device 54 may be given without hesitation to youngsters who heretofore were considered too young to indulge in the fascinating, though hazardous, pastime of roller skating, for the instant brake device may be adjusted to the extent where the wheels of the skate will hardly turn, if at all, so as to preclude all dangers involved in the use of free-wheeling skates.

While roller skates with the instant brake device are thus ideally suited to permit youngsters, heretofore considered too young to indulge in roller skating, safely to indulge in this sport, they are equally well suited for youngsters of all ages with little or no skating experience safely to learn to skate naturally by being gradually exposed to the hazards from free-wheeling rollers as they gain more and more experience in and control over riding roller skates. Thus, the instant brake device may initially be applied so as to lock or nearly lock the wheels against free-wheeling until a youngster gets the feel of roller skates and learns to balance himself instinctively when the skates roll on the ground even very slowly. The brake device may then be adjusted from time to time to release the wheels more and more as the youngster passes through progressively advanced stages in his training on roller skates until the day when he has sufficient control and experience to ride free-wheeling skates safely, at which time the instant brake device may be removed from the skates for the future natural free-wheeling use of the same. Roller skates provided with the instant brake device are suitable for safely training a youngster not only for ordinary roller skating, but also for fancy or trick skating if the youngster or even a grown-up has the desire and ambition to learn the more advanced varieties of roller skating.

The instant brake device is of extremely simple construction and lends itself to efficient and exceedingly inexpensive mass production. The preferred form of the instant brake device as an accessory which is readily attachable to and detachable from conventional roller skates is of considerable advantage, in that the same may be purchased as inexpensive units by the public and attached to conventional roller skates until a youngster becomes an accomplished skater, whereupon these brake units may be discarded or given away to some other youngster with the thought that they were well worth their low purchase price in view of the protection that had been afforded by them in the course of learning to roller skate.

Figs. 4 and 5 show a modified brake device 80 applied to the rear wheels 16 only of a conventional roller skate. This modified brake device 80, which is also shown in perspective in Fig. 6, comprises a relatively rigid brake plate or member 82 of any suitable brake material, in

this instance wood, and a brake applicator 84. The brake member 82 is in its installed condition adapted to be inclined to the foot rest 12, and to bear with one end against the customary down-turned flanges 86 on the heel plate 20, and with an opposite end length thereof against the rear wheels 16. To provide substantial contact areas between the brake member 82 and the rear wheels 16, the former is provided at its lower end with opposite curved wells 86 and 88 in which the peripheries of the respective rear wheels 16 fit. The brake applicator 84 is, in this instance, in the form of a rod 90 having one end formed into a laterally extending eye 92 and having its other end threaded for the reception of a wing nut 94. The rod 90 extends through the brake member 82 and, in the installed condition of the brake device 80, rests against the base portion 34 of the bracket 30 of the rear wheel mount 28, with the laterally extending eye 92 abutting the side flange 36 of the bracket 30. In assembling the instant modified brake device 80 with 20 the roller skate, the eye 92 of the rod 90 is passed between the opposite legs 32 of the U-shaped bracket 30 and then brought against the side flange 36 on the latter, whereupon the brake member 82 is drawn against the side flanges 86 on the heel plate 20 and against the peripheries 25 of the rear wheels 16 on appropriately turning the wing nut 94 on the threaded end of the rod 90. The brake member 82 will be forced into braking engagement with the rear wheels 16 with a force depending on the extent of tightening the wing nut 94, as will be readily understood. Accordingly, the instant modified brake device 80 has all the advantages of the previously described brake device 54, and functionally distinguishes from the latter by being applicable to the rear wheels only of a conventional roller skate.

35 Figs. 7 and 8 show further modified brake devices 100 which are applicable in pairs either to the front wheels or the rear wheels, or both, of a conventional roller skate. In this instance, a pair of these modified brake devices 100 is shown applied to the rear wheels 16 of a roller skate. These brake devices 100 are identical and each consists of a mere washer 102 which is of general dish-shape and made preferably from slightly springy metal. The hub 104 of each washer 102 is centrally apertured and passed over the adjacent threaded end 106 of the fixed rear axle 24, and is suitably splined thereto as at 108 so as to be non-rotatable, but axially movable, on the adjacent axle end 106. The pair of washers 102 are on the outside of the customary nuts 110 which hold the inner races 112 for the anti-friction wheel bearings 114 on the axle 24, against the axle-socket 48 of the rear wheel mount 28 (Fig. 8). Each washer 102 is preferably formed to provide fingers 116 which radiate from the hub 104 and engage the outer side of the adjacent wheel 16. Each washer 102 is forced with its fingers 116 into braking engagement with its wheel 16 by a nut 118 on the adjacent axle end 106. Obviously, the washers 102 will be forced into braking engagement with the adjacent wheels 16 with forces that depend on the extent of tightening the respective nuts 118.

60 Usually, the axles of conventional roller skates extend sufficiently beyond the customary end nuts 110 thereon to permit the installation of the instant brake washers 102 and brake applicator nuts 118, after first cutting slots in the axle ends for the splined reception of the washers 102. If the cutting of slots in the axle ends of existing roller skates should be a task too difficult for some, recourse may be had to two brake applicator nuts 118 on each axle end between which a brake washer 102 may be clamped against rotation on the axle end, or each brake 65 washer 102 may be permanently joined, as by welding, for instance, to its nut 118, and an additional lock nut used to prevent unauthorized turning of the nut 118 on its respective axle end 106.

70 The invention may be carried out in other specific ways 75 than those herein set forth without departing from the

spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a roller skate having a foot rest and two pairs of rotary front and rear wheels on opposite sides of depending front and rear mounts, respectively, on the foot rest, the combination of a plate-like brake member interposed between the foot rest and the adjacent peripheries of said wheels, said member having opposite forked ends bearing against the peripheries of the wheels of said pairs, respectively; and means forcing said forked ends of the brake member at all times into braking engagement with the peripheries of the wheels of the respective pairs, thereby substantially preventing free-rolling of the skate on the ground when all wheels rest thereon.

2. The combination in a roller skate as set forth in claim 1, in which said means engages said brake member intermediate the opposite forked ends thereof and is manually operable to force the latter with a variable force into braking engagement with the peripheries of the wheels of the respective pairs.

3. The combination in a roller skate as set forth in claim 1, in which said means comprises a manually turnable screw in threaded relation with said brake member intermediate the opposite forked ends thereof and bear-

ing with one end against the foot rest, for forcing the opposite forked ends of said brake member with a variable force into braking engagement with the peripheries of the wheels of the respective pairs.

4. For use with a roller skate having a foot rest and two pairs of rotary front and rear wheels on opposite sides of depending front and rear mounts, respectively, on the foot rest, an attachable and detachable brake device comprising a plate-like brake member having opposite forked ends of sufficient lengths to permit sliding said brake member intermediate the foot rest and wheels and resting said opposite forked ends against the adjacent peripheries of the wheels of said pairs, respectively, with clearance from the adjacent mounts, respectively; and a manually turnable screw in threaded relation with said brake member intermediate the opposite forked ends thereof and adapted to bear with one end against the foot rest.
